UNITED STATES PATENT OFFICE

BENJAMIN W. TAYLOR, OF BAYSIDE, NEW YORK, ASSIGNOR TO THE SKAYEF BALL BEARING COMPANY, OF HARTFORD, CONNECTICUT, A CORPORATION OF CONNECTICUT

MOUNTING OF ANTI-FRICTION JOURNAL BEARINGS IN RAILWAY-TRUCK SIDE FRAMES

Application filed June 21, 1928. Serial No. 287,152.

The object of this invention is to form seats for mounting roller and other anti-friction bearings directly in the ends of the side frames of railway trucks. In doing this, openings are formed at the ends of the frame member which present walls completely surrounding the outer member of the anti-friction bearing.

One practicable example of the invention is illustrated in the accompanying drawings, in which

Figure 1 represents a railway truck side frame having at one end a cap or closure for the end of the axle and the bearing, the other end showing this cap removed and the bearing in position.

Fig. 2 is an enlarged top view of the right-hand end of the construction shown in Figure 1, and

Fig. 3 is a central section taken at about the plane of the lines 3—3 in Figs. 1 and 2, this view being shown approximately of the same scale as Fig. 2.

The frame 4 illustrated herein is in the main a standard form of railway truck side frame which I have modified to produce a mounting for an anti-friction bearing, a roller bearing being shown in the present illustration. Heretofore, frames substantially

of this type have been formed at their ends with recesses for receiving journal boxes. According to my invention, I modify the ends and bore out or otherwise form an opening 5 extending from side to side of each end. The walls of this opening are continuous for surrounding the outer member or ring 6 of the anti-friction bearing. In the illustration the inner ring 7 of the roller bearing is mounted upon the journal end 8

of the car axle 9 through the medium of a taper sleeve 10.

The end of the journal is shown screw threaded at 11 for receiving a suitable nut 12 which is held in position by the locking device 13, which in turn is held in position by a pair of cap screws 14. Two sets of rows of rollers 15 are shown mounted between the outer and inner-races 6 and 7, these parts being constructed for carrying both radial and axial loads.

The bearing, according to the construction illustrated, may be removed from the axle by first removing the cap screws 14 and the locking device 13, then unscrewing the removing nut 12, after which a puller may be applied in back of the head 16 of the taper sleeve 10 for pulling this off the journal end 8.

The form of the opening in the ends of the side frame 4 follows the prevailing practice in mounting the type of bearing illustrated, namely, in forming a pad 17 at its upper portion comprising somewhat less than 180° for resting upon and closely embracing the upper portion of the outer ring or member 6, the lower portion being cut away as in 18 for freeing the bearing seat from the lower portion of the ring 6.

A cap 19 is shown forming a closure for the outer end of the opening 5 and for the parts mounted therein, and a cap, 20 is shown provided for closing the other side or rear of the opening. These caps are preferably held in their closed position by a series of bolts 21. A positioning device, as for instance a pin 22 may be applied for locating one of the covers in its upper radial position.

The inner or rear cover 20 is shown cooperating with labyrinth forming members, but as these do not specifically form any part of the present improvement, their details will not be described.

The covers 19 and 20 are shown provided with inwardly directed flanges 23 and 24 for positioning them and also limiting the lateral movement of the outer bearing ring 6, as this moves back and forth with a car movement.

For convenience of illustration, a part only of the truck has been illustrated, and the wheels have been omitted. However, it will be assumed that the wheel occupies a position on the axle 9 to the right of the part shown in Fig. 3.

The bearing mounted on the axle may be assembled with the side frame by presentation from the rear side, the right-hand side in Fig. 3, or the bearing may be entered into the housing and its seat from the left-hand

side. In practice, it may be found desirable to mount the bearing upon the journal, and also mount the rear closure member 20 in position and present this assembled structure to the opening 5 from the rear side. Or, in some instances it may be found desirable to mount the bearing in the opening 5 from either side and assemble the parts by introducing the axle into the sleeve 10. The bearing itself may be removed from the axle and from the opening 5 in the side frame upon jacking up and applying the lifting force at about the point 25, whereupon by unscrewing the nuts 26, the bolts 24 will remain in place holding the rear cover 20 when the front cover 19 may be removed, and the bearing removed from the axle and its seat in the manner previously described, whereupon inspection and repair or replacement of a new bearing may be effected.

This ability to remove the bearing without removing the axle from its position in the truck is a great advantage, since this repair may be done anywhere on the road.

25 Although but one form of the invention has been illustrated and particularly described, yet it is to be understood that various changes may be made as occasion demands within the scope of the claims without departing from the spirit of my invention.

Having described my invention, I claim and desire to secure by Letters Patent:

1. As an article of manufacture, a railway truck side frame, having at each of its ends an opening extending completely through it from side to side, the wall of each opening being continuous and forming a seat for surrounding the outer member of an anti-friction bearing, and constructed and adapted to receive such anti-friction bearing from either side.

2. As an article of manufacture, a railway truck side frame, having at each of its ends an opening extending completely through it from side to side, the wall of each opening being continuous and forming a seat for surrounding the outer member of an anti-friction bearing, and constructed and adapted to receive such anti-friction bearing from either side, and removable closures for both sides of the openings.

3. As an article of manufacture, a railway truck side frame, having at each of its ends an opening extending completely through it from side to side, the wall of each opening being continuous and forming a seat for surrounding the outer member of an anti-friction bearing, and constructed and adapted to permit the removal of such anti-friction bearing from either side.

4. As an article of manufacture, a railway truck side frame, having at each of its ends an opening extending completely through it from side to side, the wall of each opening

being continuous and forming a seat for surrounding the outer member of an anti-friction bearing, removable closures for both sides of the openings, and constructed and adapted to permit the removal of such anti-friction bearing from either side.

5. The combination with a railway car axle, having an anti-friction bearing mounted upon it, such bearing comprising an inner ring, an outer ring and rolling elements therebetween, a railway truck side frame having an opening in its end extending completely through it from side to side, the wall of such opening being continuous and forming a seat for surrounding the outer ring, removable closures for both sides of the opening, the parts being so constructed and adapted that upon the removal of the outer cover the anti-friction bearing may be removed from the seat and axle while these parts are in position in the truck and under the car, or upon removal of the inner closure the axle and bearing may be removed from the seat.

Signed at New York, N. Y., this 19th day of June, 1928.

BENJAMIN W. TAYLOR.
